Filed May 22, 1972, Ser. No. 255,927

Term of patent 14 years

Int. Cl. D3—02

U.S. Cl. D87—1 D

FIG. 1 is a top plan view of a rotatable cassette holder showing my new design;

FIG. 2 is a side elevational view, the opposite side being substantially the same in appearance as the side shown;

FIG. 3 is a bottom plan view thereof;

FIG. 4 is a horizontal fragmentary sectional view as seen from the plane 4—4 in FIG. 2; and

FIG. 5 is a vertical fragmentary sectional view as seen from the plane 5—5 in FIG. 1.

I claim:

The ornamental design for a rotatable cassette holder, substantially as shown and described.
